(57) **CLAIM**

The ornamental design for a lid, as shown and described.

DESCRIPTION

FIG. 1 is a right-side perspective view of a lid showing my new design;

FIG. 2 is a front elevation view thereof;

FIG. 3 is a back elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a right-side perspective view thereof, as applied to a drinking container.

The broken lines shown in the drawings are shown for illustrating unclaimed portions of the article and presently, form no part of the claimed design.
